UNITED STATES PATENT OFFICE.

LOUISE AVERILL COLE, OF BOSTON, MASSACHUSETTS, ASSIGNOR TO G. & C. MERRIAM COMPANY, OF SPRINGFIELD, MASSACHUSETTS, A CORPORATION.

DESIGN FOR A BOOK-COVER.

40,403.

Specification for Design.

Patented Dec. 14, 1909.

Application filed October 25, 1909. Serial No. 524,584. Term of patent 14 years.

To all whom it may concern:

Be it known that I, LOUISE AVERILL COLE, a citizen of the United States of America, residing at Boston, in the county of Suffolk, State of Massachusetts, have invented a new, original, and ornamental Design for Book-Covers, of which the following is a specification, reference being had to the accompanying drawing, forming part thereof.

The figure is a plan view of a book cover showing my design.

I claim:

The ornamental design for a book-cover, as shown.

LOUISE AVERILL COLE.
